UNITED STATES PATENT OFFICE.

HARTSON C. McCALL, OF WASHINGTON, DISTRICT OF COLUMBIA.

DESIGN FOR A SIGN.

Application filed August 27, 1925. Serial No. 14,618. Term of patent 14 years.

To all whom it may concern:

Be it known that I, HARTSON C. McCALL, a citizen of the United States of America, residing at Washington, District of Columbia, have invented a new, original, and ornamental Design for a Sign, of which the following is a specification, reference being had to the accompanying drawing, forming a part hereof.

In the drawing:

Fig. 2 is an edge view of the same.

I claim:

The ornamental design for a sign, as shown.

HARTSON C. McCALL. [L.S.]
